WINDING APPARATUS

Horace D. Stevens, Sarasota, Fla., assignor to The Firestone Tire & Rubber Company, Akron, Ohio, a corporation of Ohio

Application December 26, 1951, Serial No. 263,271

9 Claims. (Cl. 242—56)

1

This invention relative to apparatus for continuously winding sheet material and more particularly to improved apparatus capable of winding sheet material on successive spools without interruption.

Apparatus according to the present invention is adapted to receive sheet material such as calendered plastic film from a calender and to wind it into rolls of the desired size without interrupting the operation of the calender and the wind-up apparatus. The present apparatus, like that disclosed in my co-pending application, Serial No. 42,383, filed August 4, 1948, has two wind-up spindles, one spindle receiving and winding the material while the other spindle, termed the stand-by spindle, is made ready to receive and wind the material when its turn comes in the next cycle of operation. When the winding spindle is fully loaded, a changeover is made to the stand-by spindle which begins winding automatically. During the changeover, there is a brief instant of time during which the sheet material is momentarily secured to both spindles to place a portion of the sheet under tension. At this instant the stretched sheet is severed, and the winding proceeds on the new spindle. The other spindle is then unloaded and made ready for its next winding period of operation.

In the present invention the wind-up spindles are stationary, and the sheet material is fed onto one or the other of the spindles by transfer rolls which shift their position to cooperate successively with the wind-up spindles. The transfer rolls have associated cutting means to sever the sheet in the manner described. The apparatus provides a rugged, serviceable, and effective means of achieving the objects which are set out in part below.

A general object of the invention is to provide a method and apparatus which enables a web of sheet material to be wound successively on each of a plurality of wind-up spindles without interrupting the continuous feeding movement of the sheet material.

A more specific object is to provide apparatus of the type described which attaches the sheet material to the next successive wind-up spindle prior to or substantially simultaneously with the severing of the sheet material to part it from the preceding wind-up spindle.

Another object is to provide wind-up apparatus whose speed of winding is maintained equal to the feeding of sheet material to the apparatus.

Another object is to provide apparatus which effectively controls the sheet material being

2

wound without creating loose, flapping ends of sheet material.

Other objects are to provide apparatus which is rugged and simple in construction, which is dependable in operation, and which is easy to repair and maintain.

These and other objects and advantages will be more fully apparent from the following description of a preferred form of the invention, reference being had to the accompanying drawings in which:

Figure 1 is a sectional view of apparatus embodying the invention taken in the plane 1—1 of Figure 2;

Figure 2 is a sectional view taken in the plane indicated by the lines 2—2 of Figure 1;

Figure 3 is a diagrammatic sketch of the main parts of the apparatus of Figure 1 in side elevation showing the sheet material being wound on the lower wind-up spindle;

Figure 4 is a view similar to Figure 3 showing the sheet material being severed and transferred to the upper wind-up spindle;

Figure 5 is a view similar to Figures 3 and 4 showing the apparatus in the next operative position ready to transfer the winding operation back again to the first spindle; and

Figure 6 is a view similar to Figure 5 showing the apparatus transferring material back to the first spindle.

Wind-up apparatus embodying the invention, which is indicated generally at 10, is shown receiving a continuously moving, plastic sheet 11 from a calender, not shown, and winding it into rolls of the desired size on a pair of fixed wind-up spindles 12 and 13. The apparatus feeds the sheet material to a spindle until a roll of the desired yardage has been wound thereon and then without interruption of the winding secures the sheet to the other spindle and severs it from the first.

The sheet is delivered to the spindles by a carriage indicated generally at 14 which is vertically movable into positions of delivery immediately adjacent the two spindles. The carriage 14 carries a transfer frame 15 having a pair of rolls 16 and 17 mounted thereon which engage the sheet to the wind-up spindles in a manner to be described and also a pair of cutting knives 18 and 19 which sever the strip when the transfer is made from one spindle to the other.

The transfer frame 15 is mounted on carriage 14 in a manner which permits it to be rocked forwardly so that the transfer rolls 16 and 17 can press the sheet into contact with the wind-

3

up spindles and so that the cutting knives 18 and 19 can sever the sheet after the transfer is made from one spindle to the other.

The operation of the carriage and transfer frame and their associated parts can be best understood by reference to Figures 3-6, inclusive, which diagrammatically illustrate the mode of operation. In Figure 3 the carriage 14 is shown in position to deliver sheet to the lower wind-up spindle 13, the sheet passing through the carriage, over transfer roll 17, and then downward about guide roll 20 to be wound on the spindle 13. During normal winding, as in Figure 3, frame 15 is in its retracted position. When spindle 13 is full and the winding operation is to be transferred to spindle 12, the frame 15 is rocked forwardly to the position of Figure 4, in which position the transfer roll 17 presses the strip into contact with an adhesive-coated, cardboard core 21 mounted on spindle 12. The sheet is momentarily stretched taut between spindles 12 and 13, and then in the last increment of forward motion of the frame, knife 19 severs the sheet. The roll 17 and knife 19 are thus so mounted on frame 15 as to produce a slight interval between their times of operation.

As winding proceeds on spindle 12, frame 15 is retracted away from the spindle 12 into carriage 14, and the carriage then moves downwardly to the position of Figure 5 in readiness to transfer the winding operation back once again to spindle 13. The sheet is shown in Figure 5 as passing through the frame 15, around the transfer roll 16, over guide roll 22, and then finally to the spindle 13. When the winding is complete on spindle 12, frame 15 is rocked forwardly to the position of Figure 6, at which time the upper transfer roll 16 presses the sheet against another adhesive-coated, cardboard core 21 on spindle 13, and an instant later knife 18 severs the stretched sheet. Frame 15 is then retracted and the carriage 14 moved upwardly to the position of Figure 3 ready to begin its cycle of operation once again.

The carriage or frame 14 is supported for its reciprocating movement by a supporting structure indicated generally at 25, which includes a pair of vertical, cylindrical posts 26 and 27, see Figure 1, which are supported by suitable base members 28 and which are connected at the top by the tie rods 29 and 30 and cross braces 31 and 32. A framework 34 of structural members supports the associated equipment.

The carriage itself comprises a pair of identical side members 35 and 36, see Figure 2, connected by a plurality of tie rods 31, which are secured to the side members by suitable brackets 38. Cross braces 39 may be provided to add rigidity. The carriage is supported between and movable along the supporting posts 26 and 27 by a set of four guide rollers 42 which roll along the posts and which are concave in section to conform closely to the cylindrical surfaces of the posts. The carriage may, if desired, have collars secured thereto which would embrace the posts and serve to guide the carriage movement.

The carriage 14 is moved to its transfer positions adjacent the wind-up spindles 12 and 13 by means of a chain and sprocket drive mechanism which includes chains 43 trained about upper drive sprockets 44 and lower idling sprockets 45. The carriage is connected to the front halves of the chains by brackets 46, and the weight of the carriage is counterbalanced by weights 47 which are connected in the chains.

4

on the opposite side of the sprockets. The drive sprockets 44 are mounted on shaft 48 driven by a motor 49 and a speed reducer 50 through gears 51 and 52. Drive shaft 48 is journaled in suitable bearings 55 secured to the posts 26 and 27, and the motor and speed reducer are suitably supported as by the bracket 56.

As the carriage moves from one transfer position to another, an actuating lever or finger 57 secured to the carriage actuates limit switches 60 and 61 which are positioned in the path of travel of the finger and which control the power to the reversing motor 49. The motor will tend to over-travel somewhat, and the carriage is driven past the limit switches a slight amount until it comes in contact with the stops 63 on the base, which determine its lowermost position, and the stops 64, secured to the posts 26, which determine its uppermost position.

The transfer frame 15 comprises a pair of side members 65 of the shape shown in Figure 1 which are connected by the tie bars 66 which also have the function of supporting the cutting knives, see Figure 2. The transfer rolls 16 and 17 are journaled in a position in bearings which are supported by coil springs 67, see Figure 1, which permit the rolls to yield when they contact the wind-up spindles. This yielding movement of the rolls permits the sheet to be pressed into adhesive engagement with the wind-up spindles slightly before the knives reach their cutting position, providing for the slight time delay referred to above.

The frame 15 is supported for its rocking movement by pairs of parallel, crank arms 70, as shown in Figures 1 and 2, which have pivotal engagement with the frame as at 71 and which are secured at 72 for rotation with rock shafts 73 extending across the carriage.

The frame is rocked into and out of its transfer position by rotation of the shafts 73 by means of a rack and pinion arrangement, best shown in Figure 2, comprising a pair of vertically, reciprocable racks 75 which have sliding movement within a pair of guides 76 and which are given their reciprocal movement by a hydraulic motor indicated at 77. Each of the shafts 73 have segmental pinions 78 secured thereto having engagement with the racks. The segmental pinions have an arcuate extent of about 60 degrees to provide the required rocking movement of the frame.

It will be noted from Figure 2 that the strip 11 enters from a calender or other source of supply at the left, not shown, passes through a compensating device indicated generally at 80, and then passes through the carriage to the wind-up spindles. The compensator 80 acts as a control means for regulating the speed of the wind-up spindles with respect to the calender speed, compensating both for variations in rate of production of the calender and in the increasing peripheral speed of the wind-up rolls as the material is stored on the spindles. The compensator comprises the pairs of fixed guide rolls 81 and 82 and the dancer rolls 83 which have vertical movement within the channel members 84 of the frame. The dancer rolls are counterbalanced by an arrangement comprising chain 85, the idling sprockets 86 and 87 and counterweights 88. Control means, not shown, is associated with the dancer roll and is responsive to the movement thereof to regulate the speed of the wind-up spindles. Thus, if the wind-up spindles are drawing the sheet faster than the calender can

supply it, the dancer roll will move upward, and the control means will then reduce the spindle speeds. The counterbalancing of the dancer roll makes it sensitive to any change in the relative speeds of the calender and the wind-up spindles.

The cycle of operation is primarily under the control of feeler gages which measure the build-up of sheet on the winding spindle. These gages each take the form of an idling roller 98 mounted on a pivotal arm 91 which is normally urged into contact with the spindle. As the sheet builds up on a spindle, a pivotable arm such as 91 in contact therewith will rotate outwardly to actuate a limit switch 92 and associated control circuit generally indicated at S and comprised of apparatus readily available and familiar to those skilled in the art. The arms 91 thereby control the operation of hydraulic motor 77. At this time the motor 77 will operate the racks to rock the transfer frame forwardly to make the transfer of sheet between the spindles, and then return it to retracted position. The motor 49 then will move the carriage to its next position where it will stand ready to make the next transfer.

It should be noted that the transfer of sheet material from one wind-up spindle to the other is accomplished by first securing the sheet material to the empty spindle while it is still winding on the first spindle and then cutting the sheet while it is stretched between the spindles. It will be appreciated that the stretching of the tough, plastic sheet between the spindles facilitates the cutting thereof by the knives. The transfer is positive and eliminates any danger of losing control of a loose and flapping end of sheet material. The apparatus which performs this function is simple and dependable. It needs no fine adjustment, nor does it require any high precision of construction.

Various changes and modifications will occur to those skilled in the art all within the scope of the invention, the essential features of which are summarized in the appended claims.

What is claimed is:

1. Apparatus for continuously winding sheet material, comprising a plurality of fixed wind-up spindles, a carriage movable to positions of delivery adjacent said wind-up spindles, said sheet passing through said carriage before winding on said spindles, means mounted on said carriage to press the sheet passing therethrough into adhesive engagement with one of said spindles while said sheet is still winding on a second of said spindles, and a knife mounted on said carriage operable subsequent to the engagement of said one roll and said one spindle and adapted to sever the sheet momentarily stretched between said two spindles.

2. Apparatus for continuously winding sheet material, comprising a plurality of fixed wind-up spindles, a carriage movable within a supporting framework, a source of continuously moving sheet material, means to deliver said sheet material to said wind-up spindles at a substantially constant tension, means to move said carriage to positions of delivery adjacent said wind-up spindles, means mounted on said carriage and operable intermittently to press the sheet into adhesive engagement with one of said spindles in each of said positions of delivery while said sheet is still winding on another of said spindles, and a knife mounted adjacent said spindles adapted to sever the sheet stretched between said two spindles subsequent to the engagement of said sheet with the said one spindle.

3. Apparatus for continuously winding sheet material, comprising a plurality of fixed wind-up spindles, a carriage movable within a supporting framework, a source of continuously moving sheet material, means to deliver said sheet material to said wind-up spindles at a substantially constant tension, means to move said carriage to positions of delivery adjacent said wind-up spindles, means mounted on said carriage and operable intermittently to press the sheet into adhesive engagement with one of said spindles in each of said positions of delivery while said sheet is still winding on another of said spindles, a knife mounted adjacent said spindles adapted to sever the sheet stretched between said two spindles subsequent to the engagement of said material and said one spindle, and means responsive to the build up of sheet material on said spindles to control the cycle of operation of said carriage.

4. Apparatus for continuously winding sheet material, comprising a plurality of fixed wind-up spindles, a carriage movable within a supporting framework, a source of continuously moving sheet material, means to move said carriage to positions of delivery adjacent said wind-up spindles, a frame supported by said carriage, means to move said frame forwardly to a position adjacent said wind-up spindles and to move said frame rearwardly away from said spindles, means mounted on said frame to press the sheet into adhesive engagement with one of said spindles when said frame is moved forwardly and while said sheet is still winding on a second of said spindles, a plurality of knives mounted on said frame, one of said knives being adapted to sever the sheet stretched between said two spindles subsequent to the engagement of said material and said first-mentioned spindle.

5. Apparatus for continuously winding sheet material, comprising a plurality of fixed wind-up spindles, a carriage supported by and movable within a supporting framework, a source of continuously moving sheet material, means to move said carriage to positions of delivery adjacent said wind-up spindles, a frame supported by said carriage, means to move said frame forwardly to a position adjacent said wind-up spindles and to move said frame rearwardly away from said spindles, a pair of guide rolls mounted on said frame and disposed parallel to said spindles, and knives mounted respectively above and below said guide rolls, said sheet passing between said guide rolls and partially around one of said rolls before winding on one of said spindles, said one guide roll being adapted to press the sheet passing around it into adhesive engagement with a second of said spindles when said frame is moved forwardly while said sheet is still winding on said one spindle, the one of said knives mounted adjacent the said one guide roll being adapted to sever the sheet stretched between said two spindles subsequent to the engagement of said one roll and said second spindle.

6. Apparatus for continuously winding sheet material, comprising a pair of fixed wind-up spindles, a carriage supported by and movable vertically within a supporting framework, a source of continuously moving sheet material, means to move said carriage to positions of delivery adjacent said wind-up spindles, a frame supported by said carriage, means to move said frame forwardly to a position adjacent said wind-up spindles and to move said frame rearwardly away from said spindles, a pair of rolls mounted on said frame and disposed parallel to said spindles.

dles, and a pair of knives mounted respectively above and below said rolls, said sheet passing between said rolls and partially around one of said rolls before winding on one of said spindles; said one roll being adapted to press the sheet passing around it into adhesive engagement with the other of said spindles when said frame is moved forwardly while said sheet is still winding on said one spindle, one of said knives being mounted adjacent the said one guide roll and being adapted to sever the sheet stretched between said two spindles subsequent to the engagement of said one roll and said other spindle.

7. Apparatus for continuously winding sheet material, comprising a pair of fixed wind-up spindles, a carriage supported by and movable vertically within a supporting framework, a source of continuously moving sheet material, means to move said carriage to positions of delivery adjacent said wind-up spindles, a frame supported by said carriage, means to move said frame forwardly to a position adjacent said wind-up spindles and to move said frame rearwardly away from said spindles, a pair of guide rolls mounted on said frame and disposed parallel to said spindles, a pair of knives mounted respectively above and below said guide rolls, said sheet passing between said guide rolls and partially around one of said rolls before winding on one of said spindles, said one guide roll being adapted to press the sheet passing around it into adhesive engagement with the other of said spindles when said frame is moved forwardly while said sheet is still winding on said one spindle, the said knife mounted adjacent the said one guide roll being adapted to sever the sheet stretched between said two spindles subsequent to the engagement of said one roll and said other spindle, and means responsive to the build up of sheet material on said spindles to control the cycle of operation of said carriage and frame.

8. Apparatus for continuously winding sheet material, comprising a pair of fixed wind-up spindles, a carriage supported by and movable vertically within a supporting framework, a source of continuously moving sheet material, a balanced compensator adapted to deliver said sheet material through said carriage and to said

wind-up spindles at a substantially constant tension, means to move said carriage to positions of delivery adjacent said wind-up spindles, a rockable frame supported by said carriage, means to rock said frame forwardly to a position adjacent said wind-up spindles and to rock said frame rearwardly away from said spindles, a pair of resiliently mounted guide rolls mounted on said frame and disposed parallel to said spindles, a pair of knives mounted respectively above and below said guide rolls, said sheet passing between said guide rolls and partially around one of said rolls before winding on one of said spindles, said one guide roll being adapted to press the sheet passing around it into adhesive engagement with the other of said spindles when said frame is rocked forwardly while said sheet is still winding on said one spindle, the said knife mounted adjacent the said one guide roll being adapted to sever the sheet stretched between said two spindles subsequent to the engagement of said one roll and said other spindle, and means responsive to the build up of sheet material on said spindles to control the cycle of operation of said carriage and frame.

9. The method of continuously winding plastic sheet material, which comprises leading said sheet material between a pair of guides, winding said sheet on a fixed axis, and, while winding on said axis, moving said guides adjacent a second, fixed wind-up axis to bring said sheet adjacent thereto, securing said sheet to said second axis for winding thereon and momentarily to stretch said sheet taut between said axes, and thereafter severing said stretched and tautened sheet at a point between said axes.
